according to the present invention, part of the structure being shown diagrammatically.

Referring to the drawing, the injection pump illustrated therein is adapted to supply fuel to a multi-cylinder internal combustion engine, and the injection pump has a housing made up of the elements 1 and 2 which are fixed to each other. The housing part 1 supports for rotary movement a drive means in the form of a rotary drive shaft 3 supported for rotation about its axis and driven from the engine itself in a manner well known in the art. The rotary drive shaft or drive means 3 has an enlarged portion 4 which rotates within the housing 1, 2, and the portion 4 is formed with a bore which extends perpendicularly across the axis of the shaft 3 to form a pair of pump cylinders which are coaxial and extend radially with respect to the axis of the shaft 3, and a pair of pump pistons 5 are axially reciprocable in the pair of cylinders formed in the portion 4 of the rotary drive shaft 3. At their outer ends the pistons 5 are touching a pair of members 6 formed with bearings for rollers 7 which respectively ride along a cam surface 8 formed at the inner periphery of a cam ring 9 which is fixedly carried by the housing portion 1 between the latter and the housing portion 2, so that during rotation of the shaft 3 the rollers 7 will ride along the cam surface 8 and move toward and away from each other so that the pistons 5, which form the pump piston means, will reciprocate toward and away from each other along their pressure and suction strokes, respectively. As is well known in the art, the number of camming projections of the surface 8 corresponds to the number of cylinders in the internal combustion engine to provide during each revolution of the shaft 3 reciprocations of the pistons 5 toward and away from each other a number of times which will deliver to the several cylinders of the internal combustion engine the required fuel for driving the engine. The bore which forms the cylinders receiving the pistons 5 provides between the pistons 5 the pump chamber means 10 into which the fuel flows during the suction strokes of the pump piston means 5 and out of which the fuel flows during the pressure strokes of the pump piston means 5.

The present invention relates to fuel injection pumps. Fuel injection pumps are well known for the purpose of controlling the delivery of fuel to the cylinders of an internal combustion engine. A particular problem resides in the manner in which such fuel injection pumps are regulated for the purpose of adjusting the amount of fuel which is delivered to the internal combustion engine.

It is an object of the present invention to provide for a fuel injection pump a relatively simple structure which is capable of precisely regulating the amount of fuel which is delivered to the internal combustion engine.

Another object of the present invention is to provide a structure of this type which has no particular problem with respect to the sealing of the movable elements which are moved during adjustment of the amount of fuel delivered to the engine.

Still another object of the present invention is to provide a structure wherein a piston which participates in the adjustment of the amount of fuel delivered to the engine is capable of being guided without any interruptions so that the guiding of this piston is very precise.

An additional object of the present invention is to provide a structure of the above type where the adjustable elements which regulate the amount of fuel delivered to the engine have with respect to each other no undesirable frictional relationship during the operation of the pump.

With these objects in view the invention includes, in a fuel injection pump, a pump chamber means and a pump piston means movable, during operation of the injection pump, along pressure and suction strokes in the pump chamber means. The pump of the invention also includes a yieldable piston means as well as a means which places the yieldable piston means in communication with the pump chamber means so that the yieldable piston means will move away from the pump chamber means during the pressure strokes of the pump piston means. A cylindrical body receives, slidably, a portion of the yieldable piston means so that the latter moves further into the cylindrical body during the pressure strokes of the pump piston means, and the cylindrical body is formed with an aperture through which fuel discharges from the interior of the cylindrical body during movement of the yieldable piston means further into the cylindrical body. A conduit means communicates with the pump chamber means for directing fuel therefrom to the engine only when the aperture of the cylindrical body has been closed by the yieldable piston means, and with the structure of the invention an adjusting means is operatively connected to the cylindrical body for adjusting the latter axially so as to regulate the distance through which the yieldable piston means moves before closing the aperture of the cylindrical body, so that in this way the amount of fuel delivered to the engine during the pressure strokes of the pump piston means can be adjusted.

The novel features which are considered as characteristic for the invention are set forth in particular in the appended claims. The invention itself, however, both as to its additional objects and advantages thereof, will be best understood from the following description of specific embodiments when read in connection with the accompanying drawing in which there is shown in an axial, sectional, elevational view an injection pump constructed

A distributor means in the form of a disc 11 is located over the portion 4 of the shaft 3, and the distributor means 11 has a downwardly directed, central portion 12 which extends slidably and fluid-tightly into an axial bore of the shaft 3 formed at the upper portion of the part 4 thereof and communicating with the pump chamber 10. A pin 13 extends into bores of the portion 4 of the shaft 3 and distributor disc 11 so that the latter is constrained to rotate with the shaft 3. Between the portion 4 of the shaft 3 and the disc 11 are located a pair of spring members 14 which urge the distributor disc 11 upwardly so that its top, flat surface is pressed against a mating, downwardly directed flat surface formed at the lower side of the housing portion 2.

The distributor means 11 is formed with an axial bore 15 which communicates with the pump chamber means 10 and which is of a smaller diameter at its end adjacent to the upper control surface of the disc 11 than at its lower portion which communicates with the chamber 10. Also, the distributor disc 11 is formed with a transverse bore 16 which extends across the axial bore 15. Communicating with the transverse bore 16 are a bore 17 and a pair of bores 18 which extend between the transverse bore 16 and the upper control surface of the disc 11. The pair of bores 18 are at the same radial distance from the bore 15.

The bores 20 of the housing 2 communicate through the bores 18 with the bore 16, and the number of bores 20 is equal to the number of camming portions of the surface 8 of the cam ring 9, and the bores 20 are uni-

formly distributed about the axis of the shaft 3 so that they are at equal angular distances from each other. The housing portion 2 is also formed with a number of passages 21 equal to the number of camming portions of the surface 8 and also uniformly distributed about the axis of the shaft 3, and the bore 17 moves successively into communication with the several bores 21 during rotation of the shaft 3, only one of the bores 21 being shown in the drawing for the sake of clarity.

The housing portion 2 is also formed with a bore 22 which has its axis coinciding with the axis of the shaft 3, and the bore 22 communicates with the bore 15 as well as with a cylindrical chamber 23 which receives the solid portion 24 of a yieldable piston means 24, 25 of the invention. The portion 25 of the yieldable piston means 24, 25 is coaxial with and has a diameter larger than the portion 24 of the yieldable piston means, and the portion 25 is separate from the portion 24 of the yieldable piston means and is formed with an axial bore 26 which passes through the yieldable piston portion 25. The portion 25 of the yieldable piston means is received in the interior of a cylindrical body 27 which is guided for axial movement in a cylindrical bore formed in the housing portion 2. A pin 28 extends into a slot which is formed in the exterior surface of the cylindrical body 27, and this pin 28 forms part of an adjusting means for adjusting the axial position of the cylindrical body 27. The pin 28 is fixed eccentrically to a rotary adjusting shaft 29 supported for turning movement about its axis in a bore of the housing portion 2, and extending to the exterior of the housing portion 2 where the shaft 29 is fixed to an adjusting lever 30 which may be manually turned or which may be turned by an unillustrated governor.

The interior 32 of the cylindrical body 27, into which the portion 25 of the yieldable piston means 24, 25 slidably extends, receives in its interior also a hollow piston member 33 which has a sliding fit in the body 27 which is as fluid-tight as possible. Between the transverse top wall of the hollow piston 33 and the upper surface of the portion 25 of the yieldable piston means is a spring 34 which is compressed between the parts 33 and 25 and which urges the hollow piston 33 upwardly against a plug 35 which is threaded into the housing portion 2 and closes the bore of the latter which slidably receives the cylindrical body 27.

At its exterior surface the cylindrical body 27 is formed with an axial groove 36 which extends throughout the entire length of the cylindrical body 27, and this groove 36 communicates with a radial aperture 37 extending through the wall of the cylindrical body 27. The groove 36 provides communication between the chambers 38 and 39 in the housing portion 2 which are respectively below and above the cylindrical body 27. The chamber 38 communicates with a bore 41 which in turn communicates with the inlet opening 42 through which fuel enters into the pump.

Each of the bores 21 forms part of a discharge passage 43 whose outer end portion is enlarged and guides a valve member 44 held in the illustrated closed position by a spring 45 which urges the valve member 44 against a valve seat formed by part of the housing portion 2. The spring 45 rests against an inner shoulder formed in the discharge nipple 46 which is connected with a conduit 47 leading to the injection nozzle 48, and it is to be understood that there are as many passages 43, valves 44, nipples 46, conduits 47, and nozzles 48 as there are cylinders for the internal combustion engine, and the several bores 21 respectively form parts of and communicate with the discharge passages 43.

The fuel is delivered from the tank 52 by a pump 51 along the pressure conduit 53 to the inlet 42 of the pump housing portion 2, and a filter 54 is located in the fuel supply conduit 53. Excess fuel flows back to the tank 52 through a spring-pressed non-return valve 56 which communicates with the conduit 53 between the pump 51

and the filter 54. Thus, excess fuel will automatically open the valve 56 to flow through the return conduit 55 back to the tank 52.

The above-described pump operates as follows:

5 The pistons 5 are shown in the drawing at the end of their suction strokes. During the previous suction stroke the pump chamber 10 and all of the passages communicating therewith during the suction stroke were filled with fuel. During the continued turning of the shaft 3 10 beyond the position shown in the drawing the bores 20 are first closed by the turning of the distributor 11 to displace the openings 13 beyond the bores 20. Then the pressure strokes of the pistons 5 begin. During the movement of the pistons 5 toward each other along their 15 pressure strokes the distributor means 11 places the bore 17 in communication with one of the passages 21, 43. However, the fuel which is pressed out of the pump chamber means 10 by the pump piston means 5 during the pressure stroke thereof initially moves through the bores 15 and 22 into the chamber 23 of the means which 20 guides the yieldable piston means 24, 25, displacing the piston portion 24 out of the chamber 23 and advancing the piston portion 25 further into the interior of the cylindrical body 27 in opposition to the spring 34. The 25 movement of the yieldable piston means 24, 25 away from the pump chamber means 10 during the pressure stroke of the pump piston means 5 continues as long as the fuel in the interior 32 of the cylindrical body 27 can flow out through the aperture 37. This action continues 30 until the yieldable piston means 24, 25 closes the aperture 37, and then no more fuel can flow out of the interior 32 of the cylindrical body 27, so that the movement of the yieldable piston means 24, 25 is arrested when the piston portion 25 closes the aperture 37. During the 35 remainder of the pressure stroke of each of the pistons 5 the fuel which is pressed out of the pump chamber 10 necessarily flows through the bore 21 and along the passage 43 to open the valve 44 so that the fuel will be delivered through the conduit 47 to the nozzle 48. Immediately after the end of the pressure stroke of the pump 40 piston means 5, the suction stroke begins so that the valve 44 closes, and thus the injection of fuel is terminated. During the suction stroke of the piston means 5 the inlet passages 20 are again opened so that the fuel 45 under pressure from the fuel supply pump 51 will flow into the pump chamber means 10.

During the suction stroke of the pump piston means 5, which the pump piston means 5 carries out under the influence of centrifugal force as well as under the influence of the fuel flowing into the chamber 10, the yieldable piston means 24, 25 which had its portions 24 and 25 tightly engaging each other during the pressure stroke has these portions become separated from each other so that the fuel can flow through the bore 26 into the chamber 32, and this operation during the suction stroke of the pistons 5 is of particular advantage since the aperture 37 is initially closed. Then the spring 34 returns the yieldable piston means 24, 25 to the illustrated starting position.

60 The larger diameter of the portion 25 of the yieldable piston means with respect to the portion 24 thereof produces in the chamber 32, during the injection process, a pressure which does not rise as greatly as the pressure in the pump chamber 10.

65 The turning of the lever 30 will regulate the axial position of the cylindrical body 27. By adjusting the axial position of the cylindrical body 27, the distance that the yieldable piston means 24, 25 must move before closing the aperture 37 is determined, and in this way 70 the amount of fuel delivered to the injection nozzle at each cycle of operations is controlled. In other words, the position of the aperture 37 with respect to the piston 25 will control that portion of each pressure stroke which is devoted to the delivery of fuel into the chamber 23, and therefore this adjustment will regulate that portion

of each pressure stroke which is devoted to delivery of fuel to the cylinders of the engine. The pistons 5 always move through the same strokes and thus will always displace the same amount of fuel, so that the more fuel which can be delivered to the chamber 23 the less will go to the engines and thus positioning of the cylindrical body 27 will adjust the amount of fuel which is delivered to the engine.

It should be noted that with the structure of the invention there is no problem of maintaining a seal with the structure which adjusts the position of the cylindrical body 27, and furthermore the portion 25 of the yieldable piston means has an exterior smooth cylindrical surface which is guided about its entire circumference by the inner surface of the cylindrical body 27. This is in sharp contrast with a structure where, for example, the adjusting piston is provided with an inclined shoulder which controls an aperture such as the aperture 37. With such construction the angular position of the piston must be adjusted to adjust the moment when the inclined or helical shoulder covers or uncovers the aperture, and in addition the parts cooperate with each other frictionally in a manner which does not promote the best possible operation of the pump structure. All of these difficulties are avoided with the structure of the invention where the adjustment of the amount of fuel delivered to the engine is brought about by simply changing the axial position of the cylindrical body 27.

It will be understood that each of the elements described above, or two or more together, may also find a useful application in other types of pumps differing from the types described above.

While the invention has been illustrated and described as embodied in injection pumps, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. In a fuel injection pump, in combination, pump chamber means; pump piston means received in said pump chamber means and reciprocating therein along pressure and suction strokes during operation of the injection pump; yieldable piston means; means guiding said yieldable piston means for axial movement and placing the latter in communication with said pump chamber means for yielding axially when the pressure of fuel in said pump chamber means increases during pressure strokes of said pump piston means; a cylindrical body in which part of said yieldable piston means moves axially, said body being filled with fuel and formed with an aperture through which fuel discharges from the interior of said cylindrical body during movement of said yieldable piston means into said cylindrical body when said yieldable piston means yields during an increase in the pressure of the fuel in said pump chamber means, said yieldable piston means yielding until it closes said aperture in said cylindrical body; conduit means communicating with said pump chamber means and leading therefrom to an internal combustion engine for receiving fuel from said pump chamber means during pressure strokes of said pump piston means only after said aperture has been closed by said yieldable piston means; and adjusting means operatively connected to said cylindrical body for adjusting the latter axially with respect to said yieldable piston means so as to adjust the distance through

which said yieldable piston means moves before closing said aperture, whereby the amount of fuel delivered to the engine during the pressure strokes of the pump piston means is adjusted.

5 2. In a fuel injection pump, in combination, pump chamber means; pump piston means received in said pump chamber means and reciprocating therein along pressure and suction strokes during operation of the injection pump; yieldable piston means; means guiding said yieldable piston means for axial movement and placing the latter in communication with said pump chamber means for yielding axially when the pressure of fuel in said pump chamber means increases during pressure strokes of said pump piston means; a cylindrical body in which part of said yieldable piston means moves axially, said body being filled with fuel and formed with an aperture through which fuel discharges from the interior of said cylindrical body during movement of said yieldable piston means into said cylindrical body when said yieldable piston means yields during an increase in the pressure of the fuel in said pump chamber means, said yieldable piston means yielding until it closes said aperture in said cylindrical body; conduit means communicating with said pump chamber means and leading therefrom to an internal combustion engine for receiving fuel from said pump chamber means during pressure strokes of said pump piston means only after said aperture has been closed by said yieldable piston means, the portion of said yieldable piston means which is received in said cylindrical body being of a greater diameter than the portion thereof which communicates with said pump chamber means; and adjusting means operatively connected to said cylindrical body for adjusting the latter axially with respect to said yieldable piston means so as to adjust the distance through which said yieldable piston means moves before closing said aperture, whereby the amount of fuel delivered to the engine during the pressure strokes of the pump piston means is adjusted.

3. In a fuel injection pump, in combination, pump chamber means; pump piston means received in said pump chamber means and reciprocating therein along pressure and suction strokes during operation of the injection pump; yieldable piston means; means guiding said yieldable piston means for axial movement and placing the latter in communication with said pump chamber means for yielding axially when the pressure of fuel in said pump chamber means increases during pressure strokes of said pump piston means; a cylindrical body in which part of said yieldable piston means moves axially, said body being filled with fuel and formed with an aperture through which fuel discharges from the interior of said cylindrical body during movement of said yieldable piston means into said cylindrical body when said yieldable piston means yields during an increase in the pressure of the fuel in said pump chamber means, said yieldable piston means yielding until it closes said aperture in said cylindrical body; conduit means communicating with said pump chamber means and leading therefrom to an internal combustion engine for receiving fuel from said pump chamber means during pressure strokes of said pump piston means only after said aperture has been closed by said yieldable piston means, the portion of said yieldable piston means which is received in said cylindrical body being of a greater diameter than the portion thereof which communicates with said pump chamber means and said portions of said yieldable piston means being separate from each other, said portion of larger diameter being formed with an axial bore extending therethrough; and adjusting means operatively connected to said cylindrical body for adjusting the latter axially with respect to said yieldable piston means so as to adjust the distance through which said yieldable piston means moves before closing said aperture, whereby the amount of fuel delivered to the engine during the pressure strokes of the pump piston means is adjusted.

4. In an injection pump, in combination, rotary drive means formed with a pair of diametrically opposed coaxial cylinders extending radially with respect to the axis of said rotary drive means and said rotary drive means having between said cylinders a pumping chamber; pair of pump piston means adapted to reciprocate axially in said cylinders radially with respect to said drive means along pressure and suction strokes, said pump pistons moving toward each other and toward the axis of said drive means during their pressure strokes and away from each other and said axis during their suction strokes; yieldable piston means coaxial with said drive means; means guiding said yieldable piston means for axial movement and placing the latter in communication with said pump chamber so that said yieldable piston means will move away from said pump chamber during the pressure strokes of said pair of pump piston means; a cylindrical body coaxial with and slidably receiving said yieldable piston means, the latter moving further into said cylindrical body during the pressure strokes of said pair of pump piston means, and said cylindrical body being formed with an aperture which is closed by said yieldable piston means after the latter has moved to a given extent into said cylindrical body; conduit means communicating with said pump chamber for directing fuel therefrom to an internal combustion engine after said aperture has been closed by said yieldable piston means; and adjusting means operatively connected to said cylindrical body for axially adjusting the same so as to regulate the distance through which said yieldable piston means before closing said aperture, whereby the amount of fuel delivered through said conduit means to the engine during the pressure strokes of said pair of pump piston means can be adjusted.

5. In an injection pump as recited in claim 4, said yieldable piston means having a pair of portions respectively communicating with the interior of said cylindrical body and with said pump chamber, and the portion thereof which communicates with the interior of said cylindrical body being of a larger diameter than the portion thereof which communicates with said pump chamber.

6. In an injection pump as recited in claim 5, said portion of said yieldable piston means which is of larger diameter being separate from the portion thereof which is of smaller diameter and being formed with an axial bore extending therethrough.

7. In an injection pump as recited in claim 6, spring means urging said portions of said yieldable piston means toward each other.

8. In an injection pump, in combination, housing means formed with intake and discharge passages; rotary drive means supported for rotary movement by said housing means and formed with a pair of coaxial diametrically opposed cylinders whose common axis extends radially with respect to the axis of rotation of said rotary drive means; a pair of pump piston means reciprocating during operation of the injection pump in said cylinders, respectively, the space between said pair of pump piston means being a pumping chamber from which fuel is pumped during the pressure strokes of said pair of pump piston means and into which fuel flows during the suction strokes thereof; distributor means operatively connected to said drive means for rotary movement therewith and cooperating with said inlet and discharge passages for placing said intake passages in communication with said pump chamber during the suction strokes of said pair of piston means and said discharge passages in communication with said pump chamber during the pressure strokes of said pair of piston means; yieldable piston means placed by said distributor means in continuous communication with the pumping chamber; means guiding said yieldable piston means for movement away from said pump chamber during the pressure strokes of said pair of piston means; a cylindrical body receiving a portion of said yieldable piston means and formed with an aperture through which fuel discharges out of said cylindrical body during movement of said yieldable piston means further into the same during the pressure strokes of said pair of pump piston means, said yieldable piston means closing said aperture and said distributor means maintaining the discharge passages in communication with the pump chamber to receive fuel therefrom during the pressure strokes of said pair of pump piston means after said aperture is closed by said yieldable piston means; and adjusting means operatively connected to said cylindrical body for axially adjusting the same to regulate the distance through which said yieldable piston means moves before closing said aperture, whereby the amount of fuel delivered to the discharge passages can be regulated.
